CHILD'S VELOCIPED CHASSIS

Mercer D. Walklet, Akron, Ohio, assignor, by mesne assignments, to Blazon, Inc., Akron, Ohio, a corporation of Ohio

Filed Mar. 2, 1966, Ser. No. 1,244

Term of patent 14 years

(Cl. D34—15)

Fig. 1

Fig. 2

FIG. 1 is a perspective, taken from in front and above, showing a child's velocipede incorporating my new design.

FIG. 2 is a side elevation of the child's velocipede chassis shown in FIG. 1, omitting the seat shown in phantom in FIG. 1 for convenience of illustration.

FIG. 3 is a plan view of the child's velocipede shown in FIG. 1.

FIG. 4 is a rear elevation of the child's velocipede chassis shown in FIG. 2.

The dominant feature of my design resides in the portions shown in full line; the portions shown in phantom in the drawings are included for completeness of a showing of the velocipede.

I claim:

The ornamental design for a child's velocipede chassis, as shown and described.
